UNITED STATES PATENT OFFICE.

DANIEL W. AYLWORTH, OF SOUTH HAVEN, MICHIGAN.

WIRE-TIE.

SPECIFICATION forming part of Letters Patent No. 708,612, dated September 9, 1902.

Application filed May 21, 1902. Serial No. 108,323. (No model.)

To all whom it may concern:

Be it known that I, DANIEL W. AYLWORTH, a citizen of the United States, and a resident of South Haven, county of Van Buren, State 5 of Michigan, have invented certain new and useful Improvements in Wire-Ties, of which I hereby declare the following to be a full, clear, and exact description, such as will enable others skilled in the art to which it app- 10 pertains to make and use the same.

My invention relates to improvements in wire-ties for the crossings of the line and stay wires of wire fences; and the objects of the invention are to provide a wire-tie which can- 15 not be pulled apart or removed, although easily applied, and which will form a simple and extremely rigid form of joint. I employ this tie in connection with stays having integral lateral loops spaced to conform to the desired 20 distance apart of the line-wires to secure the line-wires to the loop; and it consists in the separate wire-fastener wrapped at its extremities about the sides of a loop and passing underneath a crimp in the line-wire, with the 25 various details of construction and combination of parts as hereinafter described, shown in the accompanying drawings, and specifically stated in the claims.

In the accompanying drawings, Figure 1 30 is a view of a looped wire-fence stay, showing the crossing line-wires and the wire-fas- tener. Fig. 2 is a view of a stay, showing the loops arranged on alternate sides thereof. Fig. 3 is a view of a loop, showing the sides 35 flattened to prevent the tie from slipping to either side. Fig. 4 shows more decided crimps in the sides of the loop for the same purpose. Fig. 5 is a transverse vertical section of the loop and line-wire taken on center of loop. Fig. 6 is a transverse horizontal section on 40 center of loop, showing the wire-fastener in place. Fig. 7 is a similar section to Fig. 5, showing the use of a common staple employed as a wire-fastener, the dotted lines showing 45 it wrapped about the sides of the loop.

In these views, 1 is the stay-wire, provided with laterally-extending loops 2.

3 represents the line-wires, which pass lon- 50 gitudinally across the loops, and 4 represents the wire-fasteners.

In the sectional views it will be seen that the fastener-wire is inserted behind the line-

wire, which is crimped at 5 to permit it to pass and also to prevent the loop from slipping along the line-wire. The extremities of 55 the fastener engage the sides of the loop, and thus rigidly lock the line-wire to the loop. In order to prevent the fastener from becoming loosened or from being pulled out of the loop, as is often done when possible by hun- 60 ters or other depredators, the extremities are closely wound about the sides of the loop at 6, thus rigidly attaching the fastener there- to, so that no strain can work them loose. If the sides of the loop are left curved, the 65 fasteners may work around the loop and stand at different angles on the fence, which will look insecure, if not actually so. To avoid this tendency, the sides of the loop are straight- 70 ened, as at 7, or curved inwardly to form rest- 75 ing-places for the coils of the fastener, beyond which they cannot move. This fastener can readily be constructed of the common form of wire staple, as shown in Fig. 7. Here the staple is first placed behind the line-wire and 75 the extremities or points toward the front. Then they are bent upward and backward and coiled about the sides of the loop, thus utilizing an article that is always at hand for this particular purpose. Some advantage is 80 gained by placing the loops upon opposite sides of the stay, which tends to brace and strengthen the fence and equalize the strains—that is, if pressure were brought against the fence one wire would pull upon 85 its loop and the next would pull upon the stay, thus giving the fence greater elasticity.

Having described my invention, what I claim as new, and desire to secure by Letters Patent, is—

1. In a fence-joint the combination with a wire-stay, of lateral loops integral therewith, a series of line-wires crossing the said loops and crimped within the loop-circle, and means for binding said line-wires to said loops, con- 95 sisting of individual wire-fasteners one for each loop, each fastener passing through the crimp in the line-wire and having its extremities wrapped about the sides of the loop, sub- stantly as described.

2. The combination with a looped stay, of a line-wire provided with a crimp situated within said loop, and a fastener therefor, con- 100 sisting of a wire passing through the crimp

in the line-wire, and closely wrapped about the sides of the loop.

3. The combination with a looped stay, the said loops extending laterally therefrom and 5 flattened on the sides, of line-wires passing across said loops, the said line-wires being provided with crimps lying within each loop and wire-fasteners wound about the flattened sides of the loops and passing within the 10 crimps in the line-wires, substantially as described.

4. In combination with a stay and line-wire, a loop laterally extending on the stay, a crimp in the line-wire located within the loop, and 15 an individual wire-tie inserted through said

crimp and engaging the edges of the loop sides adjacent to the crimps in the line-wire, free extremities of the wire-tie closely wrapped about the sides of the loop and means for preventing the wrapped extremities from slipping longitudinally on the loop, substantially as described. 20

In testimony whereof I have signed my name to this specification in the presence of two subscribing witnesses.

DANIEL W. AYLWORTH.
